HINGE

Maud L. Anderson, Aurora, Ill.

Application May 7, 1937, Serial No. 141,209

15 Claims. (Cl. 16—129)

This invention relates to improvements in hinges and more specifically to the type commonly known as concealed hinges, particularly adapted though not necessarily limited in its use for installation upon automobile doors, and one of the objects of the invention is to provide an improved type of hinge having a comparatively small depth, necessitating only a shallow cut into the stationary vertical pillar for installation.

By reason of the construction and arrangement of the parts of the hinge, a large throw-out will be permitted when the door is opened, and yet when closed the parts of the hinge will fold into a very compact arrangement.

A further object is to provide an improved hinge of this character embodying a door member and a pillar member pivotally connected together, the door member being anchored to the door, while the pillar member is connected to spaced bracket or anchor members that in turn are secured or anchored to the pillar.

The pillar member is connected to the bracket or anchor members in such a manner that the pintle or pivot pin of the hinge may be flexed or deflected when hanging or setting the door, by adjusting one of the ends of the pintle, while the other end is held stationary, and then releasing the said other end of the pintle, with the result that the door will right itself and find its own axis, after which the latter end of the pintle may again be secured.

A further object is to provide an improved hinge of this character the parts of which may be adjusted, and which will swing freely on its own axis, although a pair of such hinges are spaced apart for a substantial distance.

A further object is to provide an improved hinge of this character which will be of a simple, durable and compact construction, embodying a minimum number of parts, and in which the parts may be readily and relatively adjusted to insure the proper positioning or hanging of the door with respect to the door opening, and which will also be effective and efficient in operation.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which

Figure 1 is a view in front elevation of a hinge of this character constructed in accordance with

the principles of this invention and showing the same in position, attached to a portion of a door and a pillar member.

Figure 2 is a detail vertical sectional view taken on line 2—2, Figure 1.

Figure 3 is a horizontal sectional view taken on line 3—3, Figure 1.

Figure 4 is a view similar to Figure 3 showing the position the parts will assume when the door is closed.

Figure 5 is a view similar to Figure 3 showing the position the door will assume when opened and when the parts of the hinge have been relatively adjusted to vary the throw of the door.

Figure 6 is a view partly in elevation, partly in section and partly broken away showing a pair of hinges in position and with the door wide open.

Figures 7, 8 and 9 are detail views in elevation showing the position the door will assume with respect to the door opening and pillar member under various conditions of adjustment of the parts of the hinge with respect to each other.

Figure 10 is a detail perspective view of the pillar member of the hinge.

Figure 11 is a fragmentary view partly in perspective, partly in section and partly broken away, and in the position the parts of the hinge will assume when the door is fully opened.

Referring more particularly to the drawings, the numeral 15 designates a portion of an automobile body provided with a door opening 16; 20 the pillar and 18, the door, all of the ordinary and well known construction.

The hinge consists essentially of a door member 19 of a substantially L shaped formation, 35 provided with a portion 20 which is anchored or secured to the door 18 in any suitable manner, and is also provided with an eye 21 for receiving the pintle or pivot pin 22, and what might be termed a "pillar member" designated generally 40 by the reference numeral 23 in Figure 10.

This pillar member 23 is provided with top and bottom portions 24—25 connected together by an intermediate portion or upright 26, the latter being somewhat flexible so as to be slightly twisted, in a manner to be hereinafter set forth, to create or provide a tension therein.

The portions 24 and 25 are provided respectively with bearing openings 27—28 for receiving the ends of the pivot pin or pintle 22 for pivotally connecting the door and pillar members together.

The portions 24 and 25 may be of any desired size and configuration but are preferably comparatively thin with relation to their length and

width, and are preferably of a somewhat rectangular configuration, although the shape of these portions may be varied if desired.

The bearing openings 27—28 are preferably located in one corner of each of the respective portions and are in alignment, and the forward edge of each of the portions 24—25 is preferably shaped to respectively provide cam surfaces 29—30.

10 The portions 24—25 are also respectively provided with bearing openings 31—32 that are spaced laterally from the bearing openings 27—28 and the bearing openings 31—32 are arranged in alignment.

15 The door member 19 is pivotally connected to the pillar member 23 in such a manner that the connecting portion 26 between the portions 24—25 will form a stop (see particularly Figures 3, 5 and 11), to be engaged by a portion of the door member to limit the swinging movement of the latter about the pivot 22, in one direction, thereby forming a stop to limit the opening movement of the door.

20 The numerals 33—34 designate respectively 25 brackets or anchor members by means of which the pillar member 23 is secured or anchored to the pillar 17. These bracket members may be of any desired size and configuration, a portion of which engages and rests against the outer 30 face of the pillar member 17, and are respectively provided with laterally projecting portions 35—36, such portions being formed with or constituting an integral part of the respective face plates or face engaging portions thereof.

35 The pillar member 17 is provided with a recess 37 which opens through the face of the pillar, and one of the walls 38 of the recess is preferably undercut as at 39 for a purpose to be described.

40 In assembling the hinge, the pillar member 23 and the door member 19 are connected together by means of the pivot or hinge pintle 22, and the pillar member is pivotally connected to the bracket or anchor members 33—34 by means of pivot pins 39—40 which pass through the respective laterally extending portions 35—36, and also through the respective bearing openings 31—32, the pivot pins 39—40 being held in position in any suitable manner.

45 Mounted upon the bracket or anchor members 33—34 and extending therethrough and adjacent each of the portions 24—25 of the pillar member, are screws 41—42. The inner extremities of these screws are adapted to contact and co-operate with the cam surfaces 29—30 on the respective portions 24—25 of the pillar member, and these screws 41—42 which co-operate with each of the portions 24—25, are laterally spaced from each other and serve as a means for not only holding the pillar member in proper position 50 with respect to the anchor members or brackets 33—34, but also operate to swing the respective portions 24—25 of the pillar member 23 about the respective pivots 39—40 in a manner to be described.

55 In assembling the hinge, the pillar member 23 with the respective anchor members 33—34, are pivoted to the door member and the screws 41—42 are set with respect to the cam faces 29—30, to position the pintle or pivot pin 22 between the door member and the pillar member, so as to procure the desired swinging movement of the door member with respect to the pillar member.

60 The pillar member together with the laterally projecting portions 35—36 of the bracket or anchor members 33—34, are then inserted into the

cut-away or recessed portion 37 in the pillar 17, after which the bracket or anchor members 33—34 are secured to the face of the pillar 17 in any suitable manner such as by means of screws 43.

65 Obviously the door member 19 may be secured to the door either before or after the pillar member has been placed in position with respect to the pillar.

70 When the door has been thus hung or positioned with respect to the door opening 16, the door member swinging about the pivot 22 will cause the door 18 to swing outwardly and will avoid striking any of the edges of the frame or pillar member, and will be limited in its outward or opening movement by reason of a portion of the door member striking the connecting portion 26 of the pillar member that is disposed between the portions 24—25. During the opening and closing movement of the door member it will 75 swing between the bracket members 33—34.

75 In setting or hanging the door, it is not always possible to do so accurately and therefore some adjustment is necessary. It is for the purpose of taking care of such adjustment that the screws 41—42 which co-operate with the cam faces 29—30 of the portions 24—25 of the pillar members, are provided.

80 By referring to Figures 7, 8 and 9 of the drawings, it will be noted that there is a variation in the space 44 between the edge of the door and the adjacent face of the pillar member or frame, when the door is in a closed position.

85 The size and configuration of this space when the door is closed, is the result of the amount of adjustment made when the door is being hung and after determining the amount of swing necessary to cause the door, in its opening and closing movements, to swing clear or free of the edges of the frame and door opening.

90 In Figure 7 it will be noted that there is a comparatively small space between the edge of the door and the frame, while in Figure 8 there is shown a larger space. In Figure 9 it will be noted that this space is not uniform throughout the length of the door; as illustrated in this particular exemplification of the invention it will be noted that the space is narrower at the top than at the bottom.

95 This is necessary by reason of the aforesaid conditions and in order to make the door swing freely and properly after it is hung or set.

100 The adjustment of the door is accomplished in the following manner.

105 While it is necessary in doors of this character to provide two or more hinges, in the present exemplification only two of the hinges are shown and they are spaced from each other for a considerable distance, both being secured to the pillar member.

110 The adjustment is effected in each hinge in the same manner. Therefore, the description with respect to one hinge will apply equally as well to all of the hinges employed.

115 When the door is first hung, as is usual in hanging of all doors, the door is opened and closed carefully with respect to the door opening to see if it will swing properly and will fit properly.

120 If it is desired to raise the door slightly, it is not necessary to disconnect any of the parts from either the pillar or the door member. The adjustment is effected through the medium of the screws 41—42.

125 The adjustment will also be effected in the determined direction by swinging either the portion

24 or 25 of the pillar member about their respective pivots 39—40.

This adjustment can be clearly seen by referring to Figures 3, 4 and 5 of the drawings.

If it is desired to swing the lower portion 25 of the pillar member 23 about its pivot 40 to cause a greater opening to exist between the hinged edge of the door and the frame, such for instance as the opening shown in Figure 8, the right hand screw 42 is withdrawn from the position shown in Figure 5, while the left hand screw 41 is advanced, to swing the portion 25 about the pivot 40 and the extent of this swinging movement will be maintained by the end of the screw 41 being contacted with a portion of the cam surface 38 of the portion 25. The screw 41 is then adjusted so as to bind the parts in this position. During this adjustment of the portion 25 of the pillar member, and as the portion 26 is held against adjustment, the connecting portion 26 will be twisted, to a slight extent to create a tension or torsion therein. This adjustment will also cause one end of the pintle to be adjusted with relation to the other end thereof.

As soon as the portion 25 has been properly adjusted, the operator then withdraws both of the screws 41—42 which co-operate with the upper portion 24 of the pillar member. As soon as this portion 24 is released, the tension or torsion which has been created in the portion 26, will cause the portion 24 to right itself with respect to the portion 25, thereby moving the pintle pin to a position to move the door to the desired extent, while at the same time the door member 19 will swing freely about the pivot or pintle pin 22.

In other words, the door will right itself to find its own axis, and the door member will not bind but will swing freely about the pivot or pintle pin.

This adjustment may be effected with both of the hinges, even though they may be spaced for a considerable distance apart.

It will therefore be manifest that the adjustment of the door may be readily obtained by the mere adjustment of the screws 41—42.

After the door has righted itself in a manner just described, the screws 41—42 which have been withdrawn to permit the movement of the portion 24 of the pillar member under the tension or torsion created in the connection portion 26, will then be adjusted to hold the parts in such position.

The screws 41—52 are of such a length that no matter what is the extent of the adjustment of the respective portions 24—25 about their pivots 39—40, they will not project beyond the outer face of the bracket or anchor members.

By providing the undercut wall 38 of the recess 37, it will be manifest that the pivot or pintle pin 22 will be located in close proximity to the outer face of the pillar member and this will give a greater range of swinging movement of the door, and at the same time the entire construction, especially of the pillar member of the hinge, is such that only a comparatively shallow recess will be required for its installation.

While the preferred form of the invention has been herein shown and described, it is to be understood that various changes may be made in the details of construction, and in the combination and arrangement of the several parts, within the scope of the claims, without departing from the spirit of this invention.

What is claimed as new is:

1. A hinge of the character described, embodying a door member and a pillar member, a pivot pin connecting the members for free swinging movement with respect to each other, spaced 5 bracket or anchor members between which the pillar member is disposed, means individual to the bracket members and pivotally connecting each adjacent end of the pillar member thereto, and means individual to and disposed adjacent 10 the ends of said pillar member for adjusting one end of the latter with respect to the other end, to deflect one end of said pivot pin with respect to the other end of the pin.

2. A hinge of the character described, embodying a door member and a pillar member, a pivot pin connecting the members for free swinging movement with respect to each other, spaced 15 bracket or anchor members between which the pillar member is disposed, means individual to 20 the bracket members and pivotally connecting each adjacent end of the pillar member thereto, and means individual to and disposed adjacent 25 the ends of said pillar member for adjusting one end of the latter with respect to the other 25 end, to deflect one end of said pivot pin with respect to the other end of the pin, the last recited means operating to swing the respective ends of said pillar member about the respective points of pivotal connection between the pillar 30 member and the respective brackets.

3. A hinge of the character described, embodying a door member and a pillar member, a pivot pin connecting the members for free swinging movement with respect to each other, spaced 35 bracket or anchor members between which the pillar member is disposed, means individual to the bracket members and pivotally connecting each adjacent end of the pillar member thereto, and means individual to and disposed adjacent 40 the ends of said pillar member for adjusting one end of the latter with respect to the other end, to deflect one end of said pivot pin with respect to the other end of the pin, a portion of said pillar member serving as a stop 45 for limiting the movement of the door member in one direction about its pivot, said stop portion being correspondingly adjusted with the end of the pillar member.

4. A hinge of the character described embodying a door member and a pillar member, a pivot pin connecting them together for free relative swinging movement, means anchoring the pillar member to a pillar, means other than said anchoring means for adjusting a portion of said pillar 50 member with respect to another portion thereof for setting or hanging the door, while said another portion of the pillar member is maintained against adjustment, and means for releasing said other portion of the pillar member, whereby the 55 pillar member and door will find their own vertical axes, and the door member will swing freely about its axis.

5. A hinge of the character described embodying a door member and a pillar member, a pivot pin connecting them together for free relative swinging movement, means anchoring the pillar member to a pillar, means other than said anchoring means for adjusting a portion of said pillar member with respect to another portion thereof 65 for setting or hanging the door, while said another portion of the pillar member is maintained against adjustment, and means for releasing said other portion of the pillar member, whereby the 70 pillar member and door will find their own vertical axes.

tical axes, and the door member will swing freely about its axis, the second recited means operating to create a torsion in said pillar member, to cause the latter to right itself when the portion thereof which was initially maintained against adjustment is released.

6. A hinge of the character described embodying a member secured to a door, and a pillar member, a pin pivotally connecting said members together, means anchoring the pillar member to a pillar and means other than said anchoring means for varying the angle of the axis of said pin to cause the door member to find its own axis to properly position the door with respect to the door opening while a free swinging movement of the door member about its pivot is maintained.

7. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot between said members with respect to said pillar member.

8. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot between said members with respect to said pillar member, the said flexible connecting portion having a torsion created therein when the said bearing portions are relatively adjusted, the said torsion operating to right said bearing portions with respect to each other.

9. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot be-

tween said members with respect to said pillar member, the said means embodying rotatably adjustable members engaging portions of said bearing portions, the axes of said rotatable members operating in planes intersecting the axis of the pivotal connections between said bearing portions and said bracket members.

10. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot between said members with respect to said pillar member, the said bearing portions being provided with cam surfaces, and the last said means embodying screws engaging and operating upon said cam surfaces.

11. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot between said members with respect to said pillar member, the said pillar member being recessed into the pillar, and the outermost upright wall of the recess being undercut, the said pivotal means between said members being disposed adjacent said undercut portion, whereby the pivot will be disposed in close proximity to the outer face of the pillar of the door opening.

12. A hinge of the character described embodying a door member, a pillar member, means pivotally connecting the members together, said pillar member embodying spaced bearing portions in which the said means is journaled, and a flexible connecting portion, spaced bracket members adapted to be anchored to the pillar of a door opening, pivotal connections between the said bracket members and the respective adjacent bearing portions of the pillar member, means individual to said bearing portions for maintaining them against adjustment about their points of pivotal connection with the respective bracket members, the last said means also independently operable to swing the respective bearing portions about the respective last said pivotal connections, to vary the position of the axis of the pivot between said members with respect to said pillar member, the said flexible connecting portion having a torsion created

therein when the said bearing portions are relatively adjusted, the said torsion operating to right said bearing portions with respect to each other, the said connecting portion between the said bearing portions also serving as a step for the movement of said door member about its pivot in one direction.

13. A hinge of the character described embodying a door member and a pillar member, a pivot pin connecting them together for free relative swinging movement, and means for adjusting a portion of the pillar member with respect to another portion thereof for setting or hanging the door, while said other portion of the pillar member is maintained against adjustment, the said means embodying a pair of screws the axes of which are transverse to the axis of said pivot, said screws being selectively operable to adjust said pillar member and to permit such adjustment.

20 14. A hinge of the character described embodying a door member and a pillar member, a pivot pin connecting them together for free relative swinging movement, and means for adjust-

ing a portion of the pillar member with respect to another portion thereof for setting or hanging the door, while said other portion of the pillar member is maintained against adjustment, the said means embodying a pair of screws operable upon said pillar member to move it in opposite directions, either of said screws being operable as an adjusting screw when the other is operable to serve as an adjustment limiting screw.

15. A concealed hinge of the character described embodying a door member, a pillar member, means forming a pivotal connection between said members, means pivotally connecting said pillar member to a pillar of a door opening, and adjusting means carried by a stationary support, 15 said pillar member having a contact surface adjacent to the said support for the said adjusting means, said surface being remote from and transverse to the axis of the second recited pivotal means, said adjusting means engaging such surface for moving the pillar member about the last recited pivotal means.

MAUD L. ANDERSON.
